UNITED STATES PATENT OFFICE.

ORIE Y. BARTHOLOMEW, OF DES MOINES, IOWA.

VETERINARY OBSTETRICAL FORCEPS.

SPECIFICATION forming part of Letters Patent No. 518,580, dated April 24, 1894.

Application filed February 9, 1894. Serial No. 499,610. (No model.)

To all whom it may concern:

Be it known that I, ORIE Y. BARTHOLOMEW, a citizen of the United States of America, residing at Des Moines, in the county of Polk and State of Iowa, have invented an Improved Veterinary Obstetrical Forceps, of which the following is a specification.

My invention consists in certain details of construction of the device whereby a simple and durable extractor is provided that is free from all sharp corners and may be positively operated to open or close with one hand, as hereinafter set forth, pointed out in my claims and illustrated in the accompanying drawings, in which—

Figure 1 is a plan view of the complete device. Fig. 2 is an enlarged detail view showing one of the end pieces for the connecting rod. Fig. 3 is a transverse sectional view 20 through the end of the jaws. Fig. 4 is a perspective view of a modified form of jaw.

Referring to the accompanying drawings the reference letter A is used to indicate the stationary part of the handle having a socket 25 A² formed on its inner end with a bore extending therethrough parallel with the handle.

A³ indicates a movable handle section pivotally attached to the stationary one at A⁴ and curved outwardly and rearwardly and 30 then parallel with the stationary handle section its end A⁵ being curved outwardly and forwardly so that the handle may be readily separated by opening the hand.

B indicates a socket adapted to receive the 35 jaws, its forward end is hollowed out and a longitudinal screw threaded bore is extended therethrough. The jaws proper C are inserted in the socket B and pivoted therein on the journals B² with their inner ends curved 40 inwardly and overlapped. Slots C² are formed in said overlapping ends for purposes herein-after set forth.

D indicates a tube having screw threaded ends adapted to be inserted in said sockets 45 and of such a length as it is desired to separate the handles from the jaws.

D² indicates a bifurcated connecting piece adapted to overlap the inner ends of the jaws and D³ is a pin adapted to be extended there-

through and through the slots C² formed in 50 said ends so as to allow a lateral movement of the jaws relative to each other.

H indicates a like connecting piece adapted to be slidily connected with the movable handle portion in a similar manner and J indicates a rod screw-threaded at its ends and 55 adapted to enter screw threaded bores formed in the ends of said connecting pieces. This rod is passed through the hollow interior of the tube D and is capable of moving longitudinally therein. Fixed to the broad inner faces of said jaws are the rubber cushions J² provided for the purpose of preventing injury to the pigs, and in Fig. 4 is shown a modified form of said ends in the shape of a cup 60 with its edges rounded to avoid injury to the pigs.

It will be obvious that by my construction all corners are avoided, the hinged portion of the movable jaws protected and the part used 70 to impart motion from the handle to the jaws completely covered. It is also obvious that the concave faces of the jaws are adapted to admit elastic cushioning material or the soft flesh of a pig and hold fast the same by suc- 75 tion.

Having thus described my invention, what I claim as new therein, and desire to secure by Letters Patent of the United States therefor, is—

1. The improved veterinary obstetrical forceps, comprising the following elements, a stationary handle portion having a screw-threaded opening formed in its outer end, a movable handle portion pivoted thereto, a 85 socket having a screw threaded opening formed therein, two jaws pivoted in said socket, a tube connecting said socket and the stationary handle and a rod pivotally and slidily connected with the movable handle 90 and with said jaws to operate them when the handle is moved, for the purposes stated.

2. An improved veterinary obstetrical forceps, comprising a stationary handle with a screw-threaded opening therein, a movable 95 handle portion pivoted thereto, a socket having a screw threaded opening formed therein, two jaws pivoted in said socket and provided

with cushioned inner faces at their outer ends, slots formed in the inner ends of said jaws as set forth, a tube having screw threaded ends adapted to enter said screw threaded openings, a rod passed through said tube, a bifurcated connecting piece adapted to connect the movable handle with said rod and a like

piece to connect the rod with the movable jaws, all arranged and combined to operate as set forth.

ORIE Y. BARTHOLOMEW.
